To all whom it may concern:

Be it known that I, CHARLES W. The figure is a view of the goblet in side elevation.

The goblet comprises a foot 1 having ribs 2 and substantially plain portions 3 intermediate such ribs converging to a multi-angular stem 4 which increases somewhat in thickness to a groove 5. Adjacent the groove 5 a rib 6 is provided with a band 7 adjacent such rib composed of protuberances 8 of substantially truncated pyramidal forma-

Above the rib 10 flutes 11 swell to the full size of the goblet terminating at a groove 12 and rib 13 similar to the groove 5 and rib 6. Above the rib 13 a band 14 is provided having the same pyramid and leaf configuration as seen at the band 7 with a second rib 15 above such band and a plain top 16 to the top of the goblet.
